UNITED STATES PATENT OFFICE

144,250

DESIGN FOR A HOUSING FOR PETROLEUM DISPENSING APPARATUS

Raymond J. Kirkby, Sherman Oaks, Calif., assignor to Adel Precision Products Corp., a corporation of California

Application August 27, 1945, Serial No. 121,668

Term of patent 14 years

(Cl. D52—2)

To all whom it may concern:

Be it known that I, Raymond J. Kirkby, a citizen of the United States and residing at Sherman Oaks, in the county of Los Angeles, State of California, have invented a new, original, and ornamental Design for a Housing for Petroleum Dispensing Apparatus, of which the following is a specification, reference being had to the accompanying drawing forming part thereof, in which:

Fig. 1 is a perspective view showing a face and one side of a housing for petroleum dispensing apparatus, embodying my new design;

Fig. 2 is a perspective view showing the same face and the other side thereof; and

Fig. 3 is an elevational view of the housing showing the face thereof opposite that shown in Figs. 1 and 2.

I claim:

The ornamental design for a housing for petroleum dispensing apparatus, substantially as shown.

RAYMOND J. KIRKBY.
